(57) **CLAIM**

The ornamental design for a palette, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a top, left, front perspective view of a palette showing my new design;

FIG. 2 is a bottom, right, front perspective view of the palette; and,

FIG. 3 is a front view of the palette.

The dash-dash broken lines in the figures are for the purpose of illustrating portions of the palette that form no part of the claimed design. The dash-dot-dash broken lines illustrate a boundary of claimed design. The white region in the figures surrounding the colored region of the palette and extending to the edge of the front surface form no part of the claimed design.
